UNITED STATES PATENT OFFICE.

ALEXANDER MORTON, OF GLEN RIDGE, NEW JERSEY.

AUDION-BULB SOCKET.

Application filed December 13, 1924. Serial No. 755,739.

This invention relates to improvements in audion bulb sockets and particularly to a means for controlling the amount that the base of a bulb may be inserted into a socket, in order to prevent distortion or bending of the contact mounted on the socket, which would affect the efficient electrical contact of said contacts on the sockets with the contact studs on the base of the lamp.

An object of the invention resides in providing means adapted for attachment to molded sockets for extending into the path of movement of the base of the lamp or the pins thereon, as the base is inserted into the sockets, in order to prevent the lamp base from being inserted into the socket a distance sufficient to cause the contact pins on the ends of said base to bend the spring contacts carried by the sockets, which would affect the electrical connection between the pins on the base and the spring contacts of the sockets, and the efficient operation of the radio circuit connected therewith.

The invention includes other objects and improvements in the details of construction and the manner of carrying out the invention, which is more particularly pointed out in the following detailed description, and in the claim directed to preferred forms of the invention, it being understood, however, that various changes in the specific details of construction and arrangement of these parts may be made, within the scope of the invention as described and claimed herein.

In the drawing, forming a part of this application:

Figure 1 is a plan view of a socket, used in connection with radio sets, for receiving and mounting an audion bulb to which the present invention is applied.

Figure 2 is a vertical sectional view, taken on the line 2-2 of Figure 1.

Figure 3 is a vertical sectional view, taken on the line 3-3 of Figure 2, substantially at right angles to the section shown in Figure 2.

Figure 4 is a detail perspective view on an enlarged scale, of the stop member illustrated in Figure 2.

Figure 5 is a vertical sectional view, through a portion of a socket, similar to Figure 3, showing a slightly different form of stop member.

Figure 6 is a detail perspective view on an enlarged scale, of the stop member shown in Figure 5.

Figure 7 is a vertical sectional view,

through a bulb socket and one of the contact terminals thereof, showing still another form of stop member, secured to the socket by the binding post or wire terminal for one of the spring contacts.

Figure 8 is a detail enlarged perspective view, of the stop member shown in Figure 7.

The socket is indicated generally at 1, and is preferably formed of molded material, preferably a form of suitable insulating material, having the cylindrical portion 2, at one end of which is provided an outwardly extending flange 3, forming the base of the socket, while the opposite end is formed with an inwardly extending flange 4, formed with a pin slot 5. The pin slot is to permit the passage of the reduced positioning pin on the side of the lamp base, in order to position the lamp in a predetermined position in the socket, so that the contact pins thereon will be arranged in predetermined relation with the spring contact 6, mounted on the base flange 3, and extending inwardly in radial relation, in the manner clearly shown in Figure 1. The cylindrical portion 2 of the bulb socket may be and preferably is formed with longitudinally extending and inwardly directed guide ribs 7, molded in the tubular portions, the inner ends of which terminate with the inner periphery of the flange 4, so that the base of an audion bulb is properly guided into the tubular portion of the socket, the pin projecting from the side of the base of the lamp or bulb entering the slot 5, which is formed in the flange 4 between a pair of adjacent guide ribs 7, as clearly illustrated in Figure 2. It will thus be seen that the guide ribs 7 form a means for limiting the rotative movement of the lamp base, after the same is positioned in the socket, so that the pin may be received in the seat portion 8 in which it is held by the natural resiliency of the spring contacts 6, at which time the contact pins on the lamp base are in proper contact with said contact springs.

In the provision of a contact of this character, it will be seen that if the lamp base is forced into the socket too great a distance, the contact studs or pins on the ends of the base will force the spring contacts 6 downwardly a sufficient amount to bend these contacts, and as a result, the natural resiliency of the spring contacts 6 will not cause them to engage the ends of the contact pins on the bulb socket, when the positioning pin

is seated in the recess 8, so that the circuit with the socket and the bulb therein will not be properly completed. In order to prevent the insertion of the lamp base too great a distance into the socket, a suitable stop member is indicated at 9, in Figures 1, 2, and 3, which is positioned against the inner periphery of the cylindrical portion 2, and extends between the guide rib 7, adjacent the slot 5, the upper end being formed with a lateral extension 10, projecting inwardly of the tubular portion, which is slightly inclined, as illustrated in Figure 2, to the main portion of the stop member 9, which serves to receive 15 and limit the positioning pin carried on the base of the audion bulb, for limiting the distance the base may be inserted into the socket. The lower end of this stop member 9 is provided with another lateral extension 11 in opposite directions to the extension 10, which is formed with an opening 12, for receiving a suitable screw member 13, adapted to secure the stop member to the base flange 3, of the socket. This stop member, 20 as shown in Figures 1, 2, and 3, is positioned in the tubular portion, in longitudinal alignment with the slot 5, and is secured to the base flange 3, intermediate the point at which the contact springs 6 are secured thereto by 25 the binding post 14.

If desired, a stop member as shown at 15 in Figures 5 and 6, may be provided, having a lateral extension at one end, as indicated at 16, provided with an opening 17 for receiving 30 the screw 17', which is adapted to secure the stop member to the base flange 3' of the socket, so that the laterally extended end portion 18 directed in an opposite direction to the lateral extension 16 is positioned in the path 35 of movement of the end of the base portion of a bulb, and which, when secured in position, as shown in Figure 5, is adapted to limit the amount the lamp base may be inserted into the socket for preventing the 40 bending of the contact springs in the socket, while at the same time permitting a sufficient insertion so that the base may be rotated, for seating the positioning pin carried by the base in the recess provided therefor, so that 45 the lamp is properly positioned with the contact pins in contact with the proper spring contacts carried by the bulb sockets. This may also be accomplished by the use of 50 an angular member 19, having one portion

20 provided with an opening 21, adapted to 55 receive the usual binding post screws 22, so that the other end of said angular member, indicated at 23, will extend into the socket in a manner similar to the lateral projection 18 of the stop member 15, for engaging the 60 end of the lamp base, to limit the insertion of said lamps, into the sockets. In this case, as shown in Figures 7 and 8, the portion 20 of the angular stop member is superposed on one of the spring contacts, as illustrated 65 in Figure 7, so that an additional screw for mounting the stop member on the lamp socket is unnecessary.

From the above description, it should thus be seen that an exceedingly simple form of 70 stop member has been provided for bulb sockets, adapted to limit the insertion of the lamp base into the socket, in order to prevent the distortion or bending of the spring contacts to such a degree as to injure the efficient 75 electrical connection between said spring contact and the contact pins on the lamp base, which would otherwise occur, if the lamp base would be permitted to be inserted into the portion 2 of the socket a 80 greater distance than necessary, for the turning movement to seat the positioning pin on the socket or notch 8 formed in the tubular portion 2.

What is claimed is:

85 A bulb socket comprising a molded body formed with a cylindrical portion having an inwardly extending annular flange at one end provided with a pin slot, a plurality of guide ribs projecting inwardly in said cylindrical portion at opposite sides of said pin slot in spaced parallel relation, resilient contact members mounted on the base and projecting into the cylindrical portion in a plane lateral to the axis of said cylindrical portion, and a stop member secured to said body, and projecting in line with the slot along the inside 90 of said cylindrical portion between a pair of said ribs, said ribs cooperating to retain said stop member in alignment with the slot, 95 said stop member being formed and positioned in said socket for limiting the insertion of a bulb base in the socket for preventing distortion of said contacts beyond their limit of flexibility.

100 105 In testimony whereof I affix my signature.

ALEXANDER MORTON.
